UNITED STATES PATENT OFFICE

JOHN L. HULBERT, OF POUGHKEEPSIE, NEW YORK, ASSIGNOR TO THE DE LAVAL
SEPARATOR COMPANY, OF NEW YORK, N. Y., A CORPORATION OF NEW JERSEY

MILKING MACHINE PULSATORE

Application filed July 9, 1931. Serial No. 549,696.

My improvement relates to automatic pneumatic pulsators for cow milking machines, and particularly to those machines wherein two pairs of teat cups are operated alternately. Machines of this generic type are disclosed in the Johanson Patent No. 1,363,878 and in the Hulbert Patent No. 1,392,570. The object of the invention is to provide a pulsator wherein the action in the two pairs of teat cups will be exactly duplicated with respect to the timing of the periods of pressure and suction.

One embodiment of my invention is herein described and illustrated a pulsator with duplicate parts symmetrical about the center and in which, during operation, the time from the beginning of the movement in one direction to the beginning of the movement in the opposite direction is necessarily the same as the time from the beginning of the movement in the last named direction to the beginning of the movement in the first named direction; the connections to the two pairs of teat cups being such as to necessarily produce balanced pulsations therein.

In the accompanying drawing of the said embodiment of my invention:

Fig. 1 is a longitudinal section:

Fig. 2 is a cross section on the line 2—2 of Fig. 1; and

Fig. 3 is an enlargement of part of Fig. 1. 1, 2, 3, and 1', 2', 3' are similar multidiameter pistons, which in operation are connected together and act as one double ended piston symmetrical about the center of length.

Each of these pistons comprises one large diameter portion 1 or 1', and two small diameter portions 2 and 3 or 2' and 3', connected by portions of still smaller diameter. Each piston carries, adjacent the large diameter portion 1 or 1' a rubber gasket ring 4 or 4'. This double ended piston reciprocates in a cylinder having a central major bore 5, 5' of a size to fit the small diameter portions 2 and 3, 2' and 3', respectively, of the piston, shorter bores at opposite ends adapted to fit the large diameter portions 1, 1' respectively, and annular valve seats 6, 6' between the large bore and the small bores. Adjacent the cylinders and communicating with their ends through

passages in the heads 7, 7' are air chambers 8, 8'. Between the cylinders and air chambers and the end heads are soft rubber gaskets 9, 9' against which may seat annular valves 17, 17' on the outer ends of the pistons 1, 1'. 55

Ports 10 and 10' communicate with a source of vacuum and ports 11 and 11' with the atmosphere. 12 and 12' are restricted ports from the cylinder to the air chambers. Parallel and adjacent to the cylinder are two pulsation passages 13 and 14. Port 15 connects cylinder 5 with passage 13 and port 15' connects cylinder 5' with passage 14. Restricted ports 16, 16' connect cylinders 1 and 1', close to the valve seats 6 and 6', with the passages 13 and 14. It will be observed that the valves 17, 17', when in contact with the rubber gaskets 9, 9', divide the head area into an inner area in communication with the air chamber 8, 8' and an outer annular area shut off therefrom.

Assume that, because of the pressure in chamber 8 and the end of cylinder 1 having been relatively low and the pressure in chamber 8' and the end of cylinder 1' having been relatively high, the piston has just completed its stroke to the left. Air entering atmospheric port 11 flows through port 15 and establishes atmospheric pressure in passage 13, and also flows through the restricted port 12 80 and gradually raises the pressure in chamber 8 and the part of the left end of the cylinder inside the valve 17. At the same time air exhausts from passage 14 through port 15' and vacuum port 10' and also exhausts from the right hand end of the cylinder and chamber 8' through the restricted port 12'. Atmospheric port 11' also admits air to the small annular space inside the seat 6', while air leaking past valve seat 6' (and which might otherwise cause premature movement) is exhausted from the annular space outside such valve seat through port 16' to passage 14. 85

When the pressure in chamber 8 and the left end of the cylinder has raised and that in chamber 8' and the right end of the cylinder has dropped until the difference is great enough, the piston begins to move toward the right. The initial movement takes valve seat 17 away from gasket 9, admitting pressure 100

to the area around the seat 17, and takes gasket 4' away from seat 6', admitting full atmospheric pressure against the inner side of head 1'. The force due to these admissions of pressure to increased areas is enough to cause the piston to complete its stroke to the right almost instantaneously.

Air now enters chamber 8' through ports 11' and 12' and is exhausted from chamber 10 8 through ports 12 and 10 until the piston again moves toward the left.

The passages 13 and 14 are adapted to be connected one with one pair and the other with the other pair of a set of teat cups.

15 All ports, pistons, and passages provided at the left of the center are exactly duplicated at the right of the center, so that forces to cause movement in one direction are in turn exactly duplicated to cause movement in the 20 other direction, the pauses at the two ends will be of equal duration, and the actions in the two pairs of teat cups will be equally timed.

Although, for purposes of manufacture and 25 assembly, the piston is made in two parts, such two parts are so connected together that in operation there is only one moving element.

Having now fully described my invention, what I claim and desire to protect by 30 Letters Patent is:

1. In a milking machine pulsator, the combination of a cylinder, a reciprocable piston, 35 ports and passages, sources of high and low pressures, and two air chambers connected with opposite ends of the piston and adapted, in either end position of the piston, to be connected one with the source of high pressure and the other with the source of low 40 pressure and effect the shift of the piston toward the other end position of the piston, said piston, cylinder, ports and passages being symmetrical about the center of length of the cylinder and piston to effect equal 45 dwells of the piston at opposite end positions.

2. In a milking machine pulsator, a cylinder and piston, two equal chambers connected with opposite ends of the piston, two 50 pneumatic pulsation conduits extending longitudinally of the cylinder and piston, sources of high and low pressures and ports and passages adapted, in one end positions of the piston, to connect one conduit and one air chamber with the source of high pressure and the other conduit and the other air chamber with the source of low pressure, and adapted, in the other end position of the piston, to reverse said connections, said cylinder, piston, ports and passages being symmetrical about the center of the cylinder.

3. In a milking machine pulsator, a cylinder and piston, two equal chambers connected with opposite ends of the piston, two 55 pneumatic pulsation conduits extending lon-

gitudinally of the cylinder and piston, sources of high and low pressures and ports and passages adapted, in one end positions of the piston, to connect one conduit and one air chamber with the source of high pressure and the other conduit and the other air chamber with the source of low pressure, and adapted, in the other end position of the piston, to reverse said connections, said cylinder, piston, ports and passages being symmetrical about the center of the cylinder, said air chambers being of equal capacity and positioned alongside the two symmetrical halves of the cylinder.

4. In a milking machine pulsator, the combination of a cylinder, a reciprocable piston, ports and passages, sources of high and low pressures, and two air chambers connected with opposite ends of the piston and adapted, in either end position of the piston, to be connected one with the source of high pressure and the other with the source of low pressure and effect the shift of the piston toward the other end position of the piston, said piston, cylinder, ports and passages being symmetrical about the center of length of the cylinder and piston to effect equal dwells of the piston at opposite end positions and means, operable in the initial movement of said piston away from an extreme end position, to increase the forces to complete such movement.

5. In a milking machine pulsator, the combination of a cylinder, a reciprocable piston, ports and passages, sources of high and low pressures, and two air chambers connected with opposite ends of the piston and adapted, in either end position of the piston, to be connected one with the source of high pressure and the other with the source of low pressure and effect the shift of the piston toward the other end position of the piston, said piston, cylinder, ports and passages being symmetrical about the center of length of the cylinder and piston to effect equal dwells of the piston at opposite end positions, said piston having pressure surfaces adapted, in the initial movement of the piston, to be rendered operative to substantially increase the difference in pressures tending to move the piston in the direction of initial movement, thereby effecting a rapid completion of the piston's movement.

6. In a milking machine pulsator a cylinder, a piston reciprocable therein by pneumatic pressures, said cylinder and piston being each symmetrical about its own center of length, means to divide the area subjected to pressure in the direction of future movement into a plurality of parts under the influence of different pressures, and means whereby initial movement of the piston opens communication from a higher pressure to a lower pressure, thus greatly increasing the moving force.

7. In a milking machine pulsator, a single movable element symmetrical about its center of length, means to bring said element under the influence of opposing pneumatic pressures the resultant of which is initially opposed to movement, said pressures being relatively variable so as to cause the resultant pressure to ultimately cause movement, means for effecting said variation in pressure, and means to remove leaking pressure fluid tending to cause premature movement.

10 In testimony of which invention, I have hereunto set my hand, at Poughkeepsie, New York, on this first day of July, 1931.
